UNITED STATES PATENT OFFICE.

AXEL S. VOGT, OF ALTOONA, PENNSYLVANIA.

SIGNAL-CORD HANGER.

1,009,946.

Specification of Letters Patent. Patented Nov. 28, 1911.

Application filed April 29, 1911. Serial No. 624,003.

To all whom it may concern:

Be it known that I, AXEL S. VOGT, a subject of the King of Sweden, residing in Altoona, in the county of Blair, in the State 5 of Pennsylvania, have invented certain new and useful Improvements in Signal-Cord Hangers, of which the following is a true and exact description, reference being had to the accompanying drawings, which form a 10 part thereof.

My present invention relates to signal cord hangers of the kind suspended from the roofs of railway cars for supporting and guiding the signal cords running through 15 the cars, and the object of the invention is to provide a simple, effective and reliable construction for the purpose specified which, while having all necessary and desirable freedom to swing and accommodate itself 20 when the signal cord supported and guided by it, is pulled laterally or downward, is normally held rigid so that it is neither swung longitudinally or laterally of the car by the movement of the latter, and is prevented from rotating about its own axis. 25

The various features of novelty which characterize my invention are pointed out with particularity in the claims annexed to and forming a part of this specification. 30 For a better understanding of the invention, however, and the advantages possessed by it, reference may be had to the accompanying drawings and descriptive matter in which I have illustrated and described a 35 preferred construction embodying my invention.

Of the drawings, Figure 1 is an elevation partly in section on the line 1—1 of Fig. 2. Fig. 2 is an inverted sectional plan taken 40 on the line 2—2 of Fig. 1, and, Fig. 3 is an elevation taken at right angles to Fig. 1 and showing the cord guiding portion of the hanger.

In the drawings, A, represents the hanger proper which comprises a rod-like body portion, to the lower end of which is secured an eye member A' provided with the guide pulley B as is usual. To the upper end of the body portion of the hanger is secured a section A², which in the form shown, com-

prises a pyramidal portion A³ having convex or bulging sides A⁴ and a disk-like flange or head A⁵ at the base of the pyramidal portion.

The hanger body is mounted in a support 55 C, shown as of cup-like form and formed with an aperture B' in its lower end conforming in shape to the cross section of, and loosely receiving the pyramidal portion A³ of the hanger body and provided with 60 a seat C² against which the head A⁵ normally bears. The support B may be attached to the car roof D or other support in any suitable manner as by means of the bolts or screws E. To yieldingly hold the 65 hanger body A in the normal position shown, in which the head A⁵ rests upon the seat C², I have provided a helical spring G which has one end engaging the upper side of the head A⁵ and centered by the boss A⁶ formed 70 on the head. The spring G bears at its upper end against a spring support or abutment in the form of a disk F, detachably secured to the support C as by means of the screws F² and provided with a centering 75 boss F' on its under side.

With the construction illustrated it will be apparent that the spring G serves to normally hold the hanger body in the position shown with reference to the support C and 80 it will be obvious that by suitably proportioning the parts the spring may be made effective to prevent the body A from being swung in any direction by the ordinary motion of the car in which it is mounted, while 85 at the same time the hanger body may swing laterally or longitudinally of the car, or in a direction having both lateral and longitudinal components when necessary to accommodate a pull on the signal cord at an angle 90 to the general direction of the length of the signal cord. The pyramidal shape of the portion A³ of the hanger body in conjunction with the square shape of the aperture B' prevents any possibility of rotation of 95 the hanger body and the consequent kinking of the signal cord. The bulging shape of the sides A⁴ of the pyramidal portion A³ insures that the effectiveness of these centering provisions is maintained while permit- 100

ting a very substantial swing of the hanger body in any direction when occasion requires. While I consider it desirable to make the aperture B' polygonal in outline 5 to conform to the cross section of the pyramidal portion A³ it will be understood that neither the exact shape of the aperture B' nor the cross section of the pyramidal portion A³ forms an essential feature of the 10 invention.

The construction disclosed may be made compact and neat in appearance and as shown is self contained, the spring G being entirely inclosed by and secured within the 15 supporting member B. Moreover, it is practically impossible for the construction to get out of order, obviously a consideration of vital importance.

While in accordance with the provisions 20 of the statutes I have illustrated and described the best form of my invention now known to me, it will be apparent to those skilled in the art that changes may be made in the form of the apparatus disclosed without departing from the spirit of my invention.

Having now described my invention what I claim as new and desire to secure by Letters Patent, is:

30 1. In a signal cord hanger the combination of an elongated body formed with a support engaging head at one end and having cord guiding provisions at its other end, of a support formed with an aperture 35 through which said body passes and with a seat engaged by said head at opposite sides of said aperture when said body is in its normal position, said head being adapted to rock on a portion of said seat at one side, and to lift from a portion of said seat at the other side of said aperture when the 40 cord guiding end of said body is moved transversely to the length of the body, and yielding means tending to hold said head against said seat.

50 2. In a signal cord hanger, the combination of an elongated body formed with a head at one end and having cord guiding provisions at the other end, a hollow support formed with an aperture through 55 which said body passes, and with a seat engaged by said head at opposite sides of said aperture when said body is in its normal position, said head being adapted to rock on a portion of said seat at one side, and to lift from a portion of said seat at the other side of said aperture when the cord guiding end of said body is moved transversely to the length of the body, and a spring mounted 60 within said support and acting between it and said head to yieldingly hold the latter against said seat.

3. In a signal cord hanger, the combina-

tion of an elongated body formed with a head at one end and having cord guiding provisions at the other end, a cup-shaped support adapted to have its base secured against a car roof and formed with an aperture in its end through which said body loosely passes and with a seat engaged by 65 said head at opposite sides of said aperture when said body is in its normal position, said head being adapted to rock on a portion of said seat at one side, and to lift from a portion of said seat at the other side of said aperture when the cord guiding end of said body is moved transversely to the length of the body, a spring abutment carried by 70 said support adjacent its base, and a spring arranged within said support and acting between said abutment and said head to hold the latter against said seat.

4. In a signal cord hanger, the combination of an elongated body having at one end a pyramidal portion terminating at its base 85 in a flange head, a support provided with an aperture through which said pyramidal portion passes and shaped to prevent rotation of said pyramidal portion about its own axis therein and provided also with a 90 seat engaged by said head at opposite sides of said aperture when said body is in its normal position, said head being adapted to rock on a portion of said seat at one side, and to lift from a portion of said seat at 95 the other side of said aperture when the cord guiding end of said body is moved transversely of the length of the body, and a spring acting on said body in a direction to hold said flange against said seat.

5. In a signal cord hanger, the combination of an elongated body having at one end a pyramidal portion with bulging sides terminating at its base in a flange head, a support provided with an aperture through 105 which said pyramidal portion passes and shaped to prevent rotation of said pyramidal portion about its own axis therein and provided also with a seat engaged by said head at opposite sides of said aperture when 110 said body is in its normal position, said head being adapted to rock on a portion of said seat at one side, and to lift from a portion of said seat at the other side of said aperture when the cord guiding end of said body is moved transversely to the length of the body and a spring acting on said body in 115 a direction to hold said flange head against said seat.

6. In a signal cord hanger the combination of an elongated body formed with a support engaging head at one end and having cord guiding provisions at its other end, of a support formed with an aperture through 120 which said body passes and with a seat engaged by said head at opposite sides of said

aperture when said body is in its normal position, said head being adapted to rock on a portion of said seat at one side, and to lift from a portion of said seat at the other 5 side of said aperture when the cord guiding end of said body is moved transversely to the length of the body, said support and

head having coöperative provisions opposing rotative movement of said body about its own axis.
